UNITED STATES PATENT OFFICE.

JOHN H. THORNHILL, OF WILKES-BARRÉ, PENNSYLVANIA.

STEM WINDING AND SETTING WATCH.

SPECIFICATION forming part of Letters Patent No. 392,140, dated October 30, 1882.

Application filed January 5, 1882. Serial No. 250,843. (No model.)

To all whom it may concern:

Be it known that I, JOHN H. THORNHILL, a citizen of the United States, residing at Wilkes-Barré, county of Luzerne, and State of Pennsylvania, have invented an Improvement in Watch Movements, of which the following is a specification, reference being had to the accompanying drawings forming part thereof.

My invention relates to that part of the mechanism of a watch movement which is employed to throw the setting or the winding mechanism into or out of gear with the winding pinion, winding bar, and winding crown. Its object is to provide devices by which the movements of the movable parts of said mechanism, in the operations just mentioned, are caused by springs; its further object is to provide mechanism in which a spring of major strength and a spring of minor strength act, or operate, in the same direction to throw the setting mechanism into gear with the winding pinion, and in which the minor spring, upon the retraction of the major spring by suitable devices, and by its contractile force, causes the setting gear to be thrown out of gear with the winding pinion and the winding gear to be thrown into gear therewith, and it consists as hereinafter described and claimed.

In the drawings, Figure 1 is a top plan view of part of a watch movement embodying my invention, the winding mechanism being shown in gear with the winding pinion, and of part of a containing case of usual construction. Fig. 2 is a plan view, partly in section, of the under side of the watch movement shown in Fig. 1. Fig. 3 is a horizontal sectional plan view of part of the devices shown in Fig. 2. Fig. 4 is a sectional elevational view, on the line *x y* of Fig. 3, and Fig. 5 is a top plan view of part of a watch movement embodying my invention, the setting mechanism being shown in gear with the winding pinion, and of part of a containing case of usual construction.

A is a main or bottom plate of a watch, of usual construction.

B is the winding wheel, and C the minute wheel.

D is a plate, or yoke, intermediately of its length pivotally mounted and supported upon a yoke stud or screw D'. This yoke is, upon its under side, provided with a crown wheel

E, with a setting wheel F, and with an intermediate winding wheel G, said wheels being geared together.

The movement, and case, shown in the drawings, are provided with a winding bar K, a winding crown L, a friction sleeve N, and a winding pinion J, all of usual and well known construction. The winding pinion is geared with the crown wheel E, so that the setting 55 wheel and intermediate winding wheel are, through the instrumentalities of the crown wheel, the winding pinion and the winding bar, upon the revolution of the winding crown, caused to revolve.

The construction and arrangement of the yoke D is such that when the setting wheel is in gear with the setting mechanism the intermediate winding wheel is out of gear with the winding mechanism, and vice versa.

I is a setting spring, at one end, at E², attached to the main or bottom plate. H is a yoke spring, at one end, at F², pivotally attached to the yoke D. These springs, at their other ends, at I' and H' respectively, are pivotally attached to studs the upper ends of which extend through openings in the main or bottom plate, and the lower ends of which are mounted upon and connected with one arm of a setting and yoke-spring lever M which 70 is fulcrumed or pivoted at that screw D² of the bearing block A² which lies farthest from the winding wheel B. The arm M' of said lever is constructed and arranged to be acted upon, and operated by, the inner end of the adjustable stem g², upon the inward longitudinal movement or adjustment of the same. The winding pinion J is, at its back or inner end, provided with an enlarged bore, and, at its outer end, with a hub J' which is adapted to 75 80 85 90 95 rest and revolve in a seat or bearing formed between the bottom plate A and the front winding pinion block A².

g² is a longitudinally adjustable stem, the part O of which forms the outside pinion 95 bearings of the winding pinion J, the part Q which is the intermediate pinion bearing, and the part P which is the inside pinion bearing, of said winding pinion. The enlarged portion Q of the stem g² is of a diameter equal 100 to that of the larger bore of the pinion J, and it forms the bearing or support thereof; the

inside end P of said stem g^2 is longitudinally adjustably mounted in a bearing in the back winding pinion bearing block B². The bearing block A² is secured to the bottom plate by 5 screws D² D² and the bearing block B² is secured to the bottom plate by screws H² H².

Such being the construction of a watch movement embodying my invention, its mode of operation is as follows: In the normal adjustment of the movement or in that adjustment thereof in which the winding pinion is in gear with the winding mechanism, the winding bar is forced in to the limit of its longitudinal inward movement, as shown in Figs. 15 2 and 3. This adjustment of the winding bar causes the inward movement of the stem g^2 , the consequent shifting of the setting and yoke spring lever M, the compression or retraction of the setting spring I, the movement of the 20 yoke spring H in a direction away from the yoke, and the consequent movement of that end of the yoke to which the yoke spring H is attached in a direction the same as that of the movement of the yoke-spring stud, there- 25 upon the spring H shifts the yoke D and throws the intermediate winding wheel G into gear with the winding wheel B, in which positions of the parts named the winding crown is in gear with the winding mechanism. To throw 30 the winding crown into gear with the setting mechanism the winding bar K is pulled outward to the extent of its longitudinal movement, whereupon, the stem g^2 offering no resistance to the lever M, the setting spring I is 35 permitted to exert its force against, and to operate, the yoke D and shift the setting wheel F into gear with the minute wheel C in which positions of the parts named the setting sprung stud I' of the lever M locks the yoke D in the 40 position shown in Fig. 5 of the drawings.

My invention provides a watch movement in which the yoke or plate, employed to gear the winding pinion with the setting or with the winding mechanism, is operated in each 45 direction by the action of a spring. It further provides mechanism in which the spring H, employed to shift the yoke and throw the winding pinion into gear with the winding mechanism, acts in the same direction as, and 50 in concert with, the spring I employed to shift the yoke and throw the winding pinion into gear with the setting mechanism, with the result that springs of less size and strength than those which would otherwise have to be em- 55 ployed may be used, and the liability of their breakage be thereby, to a great extent, lessened. It also provides mechanism by which both the winding or setting devices, of the construction shown and described, may be 60 thrown into or out of gear with the winding pinion by the longitudinal adjustment of the winding bar, as well as an advantageous bearing for the winding pinion.

Having thus described my invention, I 65 claim:—

1. In a watch movement, in combination with the winding gear and setting gear re-

spectively, a plate or yoke pivotally mounted and supported intermediately of its length, and provided with gear wheels respectively 70 adapted to be thrown at will into or out of gear with the winding gear or with the setting gear by the oscillatory adjustment of said yoke, a gear wheel mounted upon, and adapted to be revolved by the winding bar, a spring 75 adapted to operate to shift the yoke and force one of its gear wheels into gear with the setting gear, and a spring adapted, upon the retraction of the first named spring, to operate to shift the yoke and force one of its gear 80 wheels into gear with the winding gear, as specified.

2. In a watch movement, in combination with the winding gear and setting gear respectively, a plate or yoke pivotally mounted 85 and supported intermediate of its length, and provided with gear wheels respectively adapted to be thrown at will, into or out of gear with the winding gear or with the setting gear, by the oscillatory adjustment of said yoke, 90 a gear wheel mounted upon, and adapted to be revolved by the winding bar, a gear wheel in gear with the gear wheels of said yoke and attached to a lever mounted and fulcrumed upon the main or bottom plate, a spring at- 95 tached to said bottom plate at one of its ends, and pivotally attached to one arm of said lever at its other end, and adapted to exert its force against, and to operate to shift, the yoke and force one of its gear wheels into gear with the setting gear, a spring having one end piv- 100 otally attached to the arm of the lever to which one of the ends of the first named spring is at- 105 tached, and having its other end pivotally attached to the yoke, and a longitudinally mov- able or adjustable winding bar having its end, or an extension thereof, in contact with the other arm of said lever, as specified.

3. In a watch movement, in combination with the winding gear and setting gear respect- 110 ively, a plate or yoke pivotally mounted and supported intermediately of its length, and pro- 115 vided with gear wheels respectively adapted to be thrown at will into or out of gear with the winding gear, or with the setting gear, by the oscillatory adjustment of said yoke, a gear 120 wheel mounted upon and adapted to be re- 125 volved by the winding bar, a gear wheel in gear with the gear wheels of said yoke and at- 125 tached to a lever mounted and fulcrumed upon the main or bottom plate, a spring attached to said bottom plate, at one of its ends, and pivotally attached to one arm of said lever at its other end, a spring of inferior strength hav- 130 ing one end pivotally attached to the arm of the lever to which one of the ends of the first named spring is attached, and arranged to exert its force in the same direction as that of the first named spring, and having its other end pivotally attached to the yoke, a longi- 130 tudinally movable or adjustable winding bar having its end, or an extension thereof, in contact with the other arm of said lever, the construction and arrangement of said parts being

such that the expansive force of the first named spring and the contractile force of the second named spring act together, to shift the yoke, and to force one of its gear wheels into gear 5 with the setting gear, and also being such that the contractile force of the second named spring, upon the retraction of the first named spring by the movement of the arm or lever to which one of its ends is attached by the longitudinal movement of the winding bar, operates 10 to shift the yoke and force one of its gear wheels into gear with the winding gear, as specified.

4. In a watch movement, in combination a 15 plate or yoke, pivotally mounted and supported, intermediately of its length, and provided with gear wheels adapted to be thrown at will into or out of gear with the winding gear or with the setting gear by the oscillatory 20 adjustment of said yoke, a winding pinion adapted to be driven by the winding bar, the bore of said pinion being, at one end, enlarged,

a longitudinal stem, or bearing provided with an enlarged portion intermediate of its length, adapted to serve as a bearing for said enlarged 25 bore, the inner end of said adjustable stem being housed, or having a bearing, in a block mounted upon the bottom plate, and a lever fulcrumed upon the bottom plate, and having one of its arms in contact with, and adapted 30 to be operated by the inner end of the adjustable stem, and having its other arm pivotally connected with the springs which are adapted to be adjusted thereby to shift said yoke and throw its gear wheels into or out of contact 35 with the winding gear, or with the setting gear, as specified.

In testimony that I claim the foregoing as my invention I have hereunto signed my name this 27th day of December, A. D. 1887.

JOHN H. THORNHILL.
